ELECTRIC DISCHARGE DEVICE

Richard M. Somers, Orange, N. J., assignor to
 Thomas A. Edison, Incorporated, West Orange,
 N. J., a corporation of New Jersey

Application November 10, 1934, Serial No. 752,401

10 Claims. (Cl. 176—122)

This invention relates to electric discharge devices of the type throughout the normal operation of which a small quantity of included metal is vaporized, providing within the device a metal vapor at low pressure through which an arc discharge takes place. More particularly my invention relates to those low pressure, metal vapor discharge devices which also contain an inert gas, or combination of gases, the gas providing a medium for a temporary or initial arc discharge whose function is to heat the device from an initially cold condition to substantial metal vaporizing temperature. While not in all aspects limited thereto, the invention is particularly applicable to discharge devices having appreciable discharge column lengths, and especially to illuminating discharge tubes.

It is an object of my invention to provide an improved device of the type above outlined which is adapted for dependable operation on commercial current supply lines.

It is another object of my invention to provide such a device which, while dependably operable on current supplies of fluctuating voltage, is characterized by a very high efficiency—i. e., ratio of power in the discharge column to power consumption from the current supply.

Still another object of my invention is to provide a device of the type outlined in which the temporary arc discharge will be dependably produced at any current supply voltage within substantially the full range of supply voltages appropriate to the maintenance of the normal vapor arc discharge.

Other and allied objects will more fully appear from the following description and the appended claims.

In the description reference is had to the accompanying drawing, of which:

Figure 1 is an illustration of a typical discharge device of the type above outlined, together with an appropriate associated circuit through which the device may be connected to the current supply;

Figure 2 is a typical curve of a function hereininafter described, plotted against gas pressure; and

Figure 3 is a curve of optimum gas pressure, as hereininafter explained, plotted against discharge column length.

Before outlining my invention proper I refer to and describe in detail the typical system illustrated in the figure. The discharge device has been illustrated as one adapted for illuminating purposes, having two anodes, and arranged for operation on an alternating current supply; it will hereinafter be obvious, however, that my in-

vention is equally available for employment with other forms of discharge devices and current supplies, such for example as single anode devices and direct current supplies, or double element tubes for alternating current operation in which each element is alternately anode and cathode.

In the figure will be seen the tube 1 having the glass or other envelope 2, the space 2' within the envelope having been evacuated of air and containing an inert gas, or combination of gases, at pressures as hereinafter more fully set forth; the gas may for example be krypton. Also within the space 2' is provided a small amount of the metal whose vapor is to form the medium for the normal arc discharge; and while I intend no limitation to any specific metal, the small pool 2'' within the space 2' in the figure may be considered as a pool of mercury. The elements of the tube are the cathode 3, the anodes 4a and 4b, and the auxiliary starting electrode 5. The cathode 3 is of the thermionic type, and by way of example has been illustrated as a folded filament which may be coated with suitable oxides or the like to increase its emission. The anodes 4a and 4b are located near the opposite end of the tube from the cathode 3, and may for example be of the usual carbon variety. The starting electrode 5 may be a conductive ring surrounding and in slight spaced relationship to the cathode 3.

The discharge current for the device may be obtained from an alternating current line through the transformer 6, which by way of illustration has been shown as an auto-transformer. One side of the line is connected through the "on-off" switch 9' to the primary terminal 6p of the transformer, while the other side of the line is connected selectively to the primary terminals 6p', 6p'' and 6p''' through the selecting switch 9''. The transformer may have the extreme secondary terminals 6a and 6b and the secondary center-tap 6c; the first two are connected respectively to the anodes 4a and 4b through the ballast resistances or lamps 8a and 8b, while the center-tap 6c is connected to the cathode 3 through the inductance coil or choke 10 both the lamp 8a—8b and the choke 10 form ballast or current-limiting impedance means for the system.

A tertiary winding 7 forming a part of the transformer 6 may be connected across the extremities of the filament or cathode 3 for heating the same.

For starting the temporary arc discharge through the gas I have illustrated herein, though purely by way of example, the starting system shown in the Figure 3 of U. S. Patent 2,013,974 to myself, which system is described in that patent

- with reference to quite similar designating numerals. With this system the armature 12' is attracted by choke 10 to open the closely-biased switch 12, and to break the circuit 10—6c—6d—12—5—3, when the cathode 3 has attained substantially normal operating temperature; a high voltage transient is thus produced across the choke and causes the initiation of the temporary arc discharge. This discharge heats 10 the device, gradually vaporizing more and more metal; and the arc discharge transfers itself (usually gradually) from the gas as a medium to the vapor as a medium, forming the normal vapor arc discharge.
- 15 It is well understood that to maintain the normal vapor arc discharge in a given system of the type described the supply voltage must be maintained above a minimum limit. It is also true, neglecting the purely theoretical case of 20 a perfect ballast, that there is a maximum value which the supply voltage must not be permitted to exceed. This upper limit of supply voltage appears to be occasioned as follows: With an increase of supply voltage there will occur some 25 increase of discharge current and hence of temperature within the device. This temperature increase causes vaporization of more of the included metal (e. g., 2''), increasing the vapor pressure, and occasions an increase of drop in 30 the discharge column. As the supply voltage and hence the temperature increase, not only does the discharge column drop rise, but the rate of its rise progressively increases; presently a temperature is reached at which the drop tends to 35 exceed the value which the supply voltage can maintain between anodes and cathode, and extinction of the discharge results. Thus the vapor arc discharge when in progress will be maintained only so long as the supply voltage 40 remains within a definite range; this may conveniently be termed the "vapor" voltage range and its limits respectively the upper and lower vapor limiting voltages.
- 45 As to the temporary arc discharge through the gas, there is in general no significant upper supply voltage limit. There is, however, a lower permissible supply voltage limit which may be termed the gas extinction voltage; if the supply voltage falls below this limit while the temporary arc discharge is in progress, extinction 50 will result. For the low vapor pressures the lower vapor limiting voltage is always exceeded by the gas extinction voltage. Accordingly the system, if it is to be used without the requirement for manipulation of its parameters during 55 operation, has a net permissible supply voltage range whose upper limit is the upper vapor limiting voltage, but whose lower limit is the gas extinction voltage.
- 60 It will of course be understood that the absolute values of the limits of both the vapor and the net permissible voltage ranges may be together adjusted upwardly or downwardly, as by changing of the transformer ratio by adjustment of tap-selecting switch 9'; and that the 65 most important characteristic of either range is the ratio of its upper to its lower limit, or its logarithmic width. For a given ballast, this ratio or width may be increased (as to both vapor and net permissible voltage ranges) by shortening the discharge column; again, for a given tube or other device this ratio or width may be increased (as to both ranges) by increasing the ballast of the system. In either case the ratio 70 or width increase, representing increased toler-

ance to supply voltage fluctuation, is obtained by increase of the relative ballast—i. e., by increase of the power in the ballast relative to that in the discharge column. It is common practice to impart to the system a sufficiently wide net permissible voltage range for operation with any particular range of supply voltage fluctuation, simply by a sufficient progressive increase of this relative ballast. But for conventional discharge devices with any ballast the gas extinction voltage is materially higher than the lower vapor limiting voltage, and the width of net permissible voltage range therefore very much less than that of the vapor voltage range; accordingly in common practice a relative ballast is employed 10 which provides a width of vapor voltage range very much greater than will be needed for supply voltage fluctuations during continuance of the vapor arc discharge, and a wholly useless tolerance thus obtains during this continuance, i. e., 15 throughout the actually useful operation of the system.

According to my invention I employ a relative ballast sufficient to make the vapor voltage range only a little wider than the range of supply voltage fluctuations, and yet maintain the net permissible voltage range just as wide as the supply range by reducing to a very low value the excess of gas extinction voltage over lower vapor limiting voltage. By this procedure I am able to 25 secure dependable operation with materially higher than usual efficiencies. The manner in which I reduce the difference above mentioned 30 may be outlined as follows:—

If for a device and system of the type described there be plotted the excess of gas extinction voltage over lower vapor limiting voltage as a function of the pressure of the included gas, it will be found that at some particular gas pressure the function attains a minimum value; 40 the curve of such a function has been illustrated as A in Figure 2, taken in connection with the left-hand set of ordinates. While for devices otherwise similar different gases will cause the corresponding functions to have their respective 45 minima at different gas pressures, I have found that for any particular gas the pressure at which the function minimum occurs is essentially independent of ballast parameters and of parameters of the discharge device proper other than 50 the length of the discharge column, or anode-cathode separation. I have further found that the gas pressure for minimum function value is for practical purposes similar to the gas pressure for minimum gas extinction voltage; this has 55 been indicated in Figure 2 by the right-hand set of ordinates—approximate gas extinction voltages—likewise applying to the curve A. According to my invention I establish the gas within 60 the device at a pressure which causes the function above mentioned to assume substantially its minimum value, or, as a satisfactory approximation, at a value which renders the gas extinction voltage a substantial minimum for example at the pressure which is the abscissa of the point P 65 on curve A.

I have further found that the function (or extinction voltage) will remain invested with a minimum value upon variation of the discharge column length if the gas pressure be varied substantially inversely with this length. Therefore, in convenient terms, I establish the gas pressure P at a value given by the expression $P = K/L$ 70 wherein L is the length of the discharge column (in convenient units) and K is a constant de- 75

pending on the gas employed (and on the units in which L is expressed and in which it is desired that P be expressed). By way of example, I have found that for the gas krypton the value of K for minimum function value should be approximately $.4/L$ atmosphere-centimeters; in other words, if $.4$ be divided by the discharge column length in centimeters, the quotient will be the proper gas pressure in atmospheres. In Figure 3 I have shown as B a curve of this optimum gas pressure in atmospheres for the gas krypton, plotted against discharge column length in centimeters. It will be understood that this curve B represents the locus of the minimum point P of a family of the curves A of Figure 2, expressed in terms of pressure for various column lengths (the locus of the point P , expressed in terms of excess voltage for various lengths, exhibiting a variation, from constancy of that excess, which is small enough to be disregarded).

The constant K for any gas is readily determined by adjusting that gas in a representative discharge device to the pressure yielding the minimum value of the function above discussed, and multiplying that pressure by the discharge column length in that tube. Because the gas pressure for minimum function value is approximated by the pressure for minimum gas extinction voltage, a satisfactory constant for practical purposes may be arrived at by adjusting the gas in a representative discharge device to the pressure yielding minimum gas extinction voltage, and multiplying that pressure by the discharge column length. In the latter case the representative device may be a simple discharge device—i. e., one from which vaporizable metal has been omitted.

I may illustrate the application of my invention by an example. Let there first be assumed a mercury-containing tube intended for operation with a mean discharge current of approximately 2 amperes and at a mercury pressure of approximately .000133 atmosphere, the tube having a discharge column length of 100 centimeters and a diameter of 2 centimeters. Let this tube be assumed filled with krypton at a pressure of approximately .00133 atmosphere, which is representative of conventional practise. With a suitable ballast, the vapor arc discharge may be maintained in this tube by a fluctuating supply voltage which maintains between terminal $6c$ and either of the terminals $6a$ and $6b$ a voltage ranging from 80 to 115 volts; the lower and upper vapor limiting voltages are accordingly 80 and 115 respectively. The gas extinction voltage, however, will be of the order of 100 volts, so that the net permissible voltage range is only 100 to 115 volts. If the system is to function on a current supply whose voltage fluctuates between limits having the ratio of 115:100, it is obvious that neither can the ballast be decreased, nor can the tube be lengthened. The excess of gas extinction voltage over lower vapor limiting voltage is approximately 20 volts, and is quite typical.

I have found that by the application of my invention to such a tube I may decrease the excess of gas extinction voltage over lower vapor limiting voltage to between 2 and 5 volts, the precise value within this small range depending on many factors such as normal tube operating temperature, room temperature, and associated circuit parameters. Using the maximum difference figure of 5 volts, I may lengthen the discharge column to such a length that the vapor voltage range is 95 to 115 volts, while still maintaining

the net permissible voltage range at the assigned 100 to 115 volt value. Since the tube at a voltage just above its original vapor limiting voltage would operate with an arc drop of very approximately .4 volt per centimeter, I may lengthen 5 the discharge column by

$$\frac{95-80}{.4}$$

or 37.5 centimeters. In round figures I may increase the discharge column length by $\frac{1}{3}$ —i. e., from 100 to 133 centimeters. A lower magnitude of ballast impedance will now serve to keep the upper limiting voltage at 115 volts. With the reduced ballast impedance the current through the lengthened tube, for any supply voltage throughout the 100 to 115 volt range, will not be far different from the current at that supply voltage through the original tube and ballast. Since the voltage drop in the discharge column is increased by 33%, an efficiency increase of very nearly 33% is obtained.

The lengthening of the tube is rendered permissible by the employment of the proper gas pressure. To determine this pressure for the lengthened tube I divide .4, the constant for krypton above mentioned, by 133, the length of the revised discharge column in centimeters, the quotient of approximately .003 being the krypton pressure in atmospheres which I employ for the 30 lengthened tube. It will of course be obvious that instead of lengthening the tube in this example I might, upon establishment of the optimum gas pressure of .004 atmosphere for the tube with its original length, have reduced both the ballast and 35 the mean supply voltage. The same result of efficiency increase without impairment of dependability of operation would be secured.

It will be understood that the voltages to which I have referred herein, except as otherwise specially qualified, are voltages measured across the primary of the transformer 6 , to which voltages there is proportional the sum of the voltages across the discharge device (1) and across the ballasting means (10 and $8a$).

It will be understood that the broader aspects of my invention are not intended to be limited by the examples set forth herein, but that the scope of the invention is intended to be expressed in the following claims:

I claim:

1. An electric discharge device including anode and thermionic cathode elements spaced apart to provide a substantial positive column space therebetween, and containing krypton at a pressure of approximately $.4/L$ atmosphere, L being the anode-cathode separation in centimeters.

2. A low pressure metal vapor discharge device including anode and thermionic cathode elements spaced apart to provide a substantial positive column space therebetween, and containing krypton at a pressure of approximately $.4/L$ atmospheres, L being the anode-cathode separation in centimeters.

3. A low pressure mercury vapor discharge device including anode and thermionic cathode elements spaced apart to provide a substantial positive column space therebetween, and containing krypton at a pressure of approximately $.4/L$ atmosphere, L being the anode-cathode separation in centimeters.

4. An electric discharge device including anode and thermionic cathode elements spaced apart to provide a substantial positive column space therebetween; ballast means adapted for serial 75

- connection with said elements to a current source; vaporizable metal within said device for providing a low pressure vapor discharge medium; and an initial heating discharge medium within said device, comprising krypton at a pressure of approximately $.4/L$ atmosphere, L being the anode-cathode separation in centimeters.
5. An electric discharge device including anode and thermionic cathode elements spaced apart to provide a substantial positive column space therebetween; ballast means adapted for serial connection with said elements to a current source; vaporizable mercury within said device for providing a low pressure mercury vapor discharge medium; and an initial heating discharge medium within said device, comprising krypton at a pressure of approximately $.4/L$ atmosphere, L being the anode-cathode separation in centimeters.
- 10 6. An electric discharge device including anode and thermionic cathode elements spaced apart to provide a substantial positive column space therebetween; ballast means adapted for serial connection with said elements to a current source; vaporizable metal within said device for providing a low pressure vapor discharge medium; and an initial heating discharge medium included in said device, comprising an inert gas at a pressure adjusted for substantially minimum gas discharge extinction voltage.
- 15 7. An electric discharge device including anode and thermionic cathode elements spaced apart to provide a substantial positive column space therebetween; ballast means serially connected with said elements and forming therewith a load circuit; means for applying voltages across said circuit; vaporizable metal within said device for providing, when hot and with voltages across said circuit above a lower limiting voltage, a low pressure vapor discharge medium between said elements; and an inert gas included in said device at a pressure adjusted to provide a gas discharge medium between said elements with substantially
- 20 a minimum excess of voltages across said circuit over the lower limiting voltage above mentioned.
8. An electric discharge device including anode and thermionic cathode elements spaced apart to provide a substantial positive column space therebetween; ballast means serially connected with said elements and forming therewith a load circuit; means for applying voltages across said circuit; vaporizable metal within said device for providing, when hot and with voltages across said load circuit above a lower limiting voltage, a low pressure vapor discharge medium between said elements; and an inert gas included in said device at a pressure adjusted to provide between said elements a gas discharge medium characterized by an extinction voltage, measured across said load circuit, of within five volts above said lower limiting voltage.
- 25 9. An electric discharge device including anode and thermionic cathode elements spaced apart to provide a substantial positive column spaced therebetween; ballast means adapted for serial connection with said elements to a current source; vaporizable metal within said device for providing a low pressure vapor discharge medium; and an initial heating discharge medium included in said device, comprising an inert gas at a pressure of approximately K/L , L being the anode-cathode separation in said device, and K being the product of anode-cathode separation and gas pressure in a simple purely gas discharge device containing similar gas at pressure adjusted for minimum discharge extinction voltage.
- 30 10. A low pressure metal vapor discharge device including anode and thermionic cathode elements spaced apart to provide a substantial positive column space therebetween and containing an inert gas at a pressure of approximately K/L , L being the anode-cathode separation in said device, and K being the product of anode-cathode separation and gas pressure in a simple purely gas discharge device containing similar gas at pressure adjusted for minimum discharge extinction voltage.

RICHARD M. SOMERS.
